United States Patent Office

Des. 184,457
Patented Feb. 17, 1959

184,457

TOY BIRD FIGURE

Bayard C. Reed, Chicago, Ill., assignor to Marvin I. Glass, Chicago, Ill.

Application February 27, 1958, Serial No. 49,817

Term of patent 3½ years

(Cl. D34—2)

I claim:

The ornamental design of a top bird figure, substantially as shown.
